Inventor:
Henry G. Saal
By L. L. Gragg Atty.

UNITED STATES PATENT OFFICE.

HENRY G. SAAL, OF CHICAGO, ILLINOIS.

HEAD TELEPHONE RECEIVER.

Application filed August 10, 1922. Serial No. 581,030.

To all whom it may concern:

Be it known that I, HENRY G. SAAL, citizen of the United States, residing at Chicago, in the county of Cook and State of Illinois, have invented a certain new and useful Improvement in Head Telephone Receivers, of which the following is a full, clear, concise, and exact description.

My invention relates to head telephone receivers of the class that includes arcuate head bands formed of spring metal and which carry watch case receiving elements that depend therefrom.

It is the general object of my invention to regulate the extent to which the watch case receiving elements depend from the head bands so that the tops of the head bands may firmly engage the tops of the heads of the wearers while the receiving portions are closely applied to the ears.

A head telephone receiver constructed in accordance with the preferred embodiment of the invention is provided with a pair of ears upon each end of the arcuate head band thereof, the ears of each pair being so placed as to form a slot therebetween that is transverse to the head band. The ears of each pair have aligned openings that are perpendicular to the slot between such ears. A yoke is provided upon each receiving element between whose ends such element is mounted to swing so as to be adjustable to lie close to the ear of the wearer. A threaded stem is provided for the yoke, this stem passing freely through the aligned openings in the pair of ears which supports the receiving element. There is an adjusting nut threaded upon the stem and disposed in the slot between the corresponding ears. By turning this nut the stem may be moved upwardly or downwardly bodily to adjust the position of the corresponding receiving element.

I will explain my invention more fully by reference to the accompanying drawing in which Fig. 1 is a perspective view illustrating the preferred embodiment thereof; Fig. 2 is a side view of a part of the structure shown in Fig. 1, a portion being shown in section; and Fig. 3 is a sectional view on line 3—3 of Fig. 2.

Like parts are indicated by similar characters of reference throughout the different figures.

The head telephone receiver illustrated includes an arcuate head band in the form of 55 spring metal. A pair of ears 2, 3 is provided upon each end of the band. The ears of each pair are so placed as to form a slot therebetween which is transverse to the 60 band.

In the preferred embodiment of the invention each pair of ears is formed by slotting a globular headed post which includes a reduced extension 4 passing through the corresponding end of the head band and surrounded by a washer 5 upon the inner side 65 of the band. The inner end of each reduced post extension 4 is upset to enable it to function as a rivet in clamping the corresponding 70 washer 5 against the head band to secure the fixed assembly of the post and band. The ears of each pair have aligned smooth openings 6 and 7 that are in the plane of the band. The ears of each pair are also so placed as to form a slot therebetween that is 75 transverse of the band and to which the openings 6 and 7 are perpendicular. A watch case receiver 8 is suspended from each end of the head band. Each such receiver 80 is carried by a yoke 9 upon and between whose ends said receiver is mounted to swing. Each yoke has a threaded stem 10 which passes freely through the aligned 85 openings 6 and 7 of the corresponding pair of ears 2 and 3. An adjusting nut 11 is disposed in the slot between the ears of each pair, this nut being threaded upon the corresponding stem. By turning the nuts the extent to which the watch case portions of 90 the receiving device depend from the arcuate head band may be readily regulated.

While I have herein shown and particularly described the preferred embodiment of my invention I do not wish to be limited the 95 precise details of construction shown as changes may readily be made without departing from the spirit of my invention, but having thus described my invention I claim as new and desire to secure by Letters 100 Patent the following:—

A head telephone receiver including an

arcuate head band formed of spring metal; a pair of ears upon one end thereof and placed to form a slot therebetween which is transverse of the band, said ears having aligned openings that are perpendicular to said slot; a watch case telephone receiver; a threaded stem carrying said receiver and

passing freely through the aligned openings in said ears; and an adjusting nut threaded upon said stem and disposed in the slot between said ears.

In witness whereof, I hereunto subscribe my name this 17th day of June A. D., 1922.

HENRY G. SAAL.
